Filed Aug. 30, 1968, Ser. No. 13,330

Term of patent 14 years

Int. Cl. D11—01

U.S. Cl. D45—10

FIG. 1 is a top plan view of a ring showing my new design;

FIG. 2 is a side elevational view;

FIG. 3 is a front elevational view;

FIG. 4 is an elevational view of the opposite side of FIG. 2; and

FIG. 5 is a developed plan view thereof on an enlarged scale.

The dominant features of the design reside in the full line portions, the conventional wording being shown in broken lines.

I claim:

The ornamental design for a ring, substantially as shown and described.
